(57) **CLAIM**

The ornamental design for a virtual presenter, as shown and described.

DESCRIPTION

FIG. 1 is a top perspective view of the new design for a virtual presenter.

FIG. 2 is a front elevation view thereof;

FIG. 3 is a back elevation view thereof;

FIG. 4 is right side elevation view thereof, which is a mirror image of the left side elevation view;

FIG. 5 is top plan view thereof;

FIG. 6 is a bottom plan view thereof; and,

FIG. 7 is top perspective view of another embodiment of the new design for a virtual presenter.

The design includes a screen, which may be any other shape, including geometric shapes and silhouettes. Broken lines are used to show attached wheels, which form no part of the claimed design.
